UNITED STATES PATENT OFFICE.

SARAH E. BRADDOCK, OF BROOKLYN, NEW YORK, ASSIGNOR OF ONE-HALF TO ALEXANDER DUNCAN PAUL, OF BROOKLYN, NEW YORK.

CORK-EXTRACTOR.

No. 899,380.

Specification of Letters Patent.

Patented Sept. 22, 1908.

Application filed May 13, 1908. Serial No. 432,633.

To all whom it may concern:

Be it known that I, SARAH E. BRADDOCK, a citizen of the United States, residing at Brooklyn, in the county of Kings and State 5 of New York, have invented new and useful Improvements in Cork-Extractors, of which the following is a specification.

This invention relates to improvements in cork extractors, the object of the invention 10 being to provide an extracting device of simple and inexpensive construction by which refractory corks may be readily and conveniently engaged and withdrawn from a bottle.

15 A further object of the invention is to provide an extracting device having a handle of convenient form for manipulation and adapted to be engaged with a hook or other permanent object to secure additional power in the 20 removal of corks which cannot be dislodged in the ordinary way.

The invention consists of the features of construction, combination, and arrangement 25 of parts hereinafter fully described and claimed, reference being had to the accompanying drawing, in which:—

Figure 1 is a perspective view of a cork extractor embodying my invention. Fig. 2 is a sectional elevation showing the device applied for extracting a stopper, indicating in 30 dotted lines the normal position of the extractor and in full lines its engaging position ready for extraction of the cork.

The tool embodies a substantially V- 35 shaped handle 1 comprising side arms 2 connected at their upper ends by a rod 3 on which is mounted a suitable grip 4. The arms 2 converge toward their lower ends and are connected with an internally threaded 40 socket 5 receiving the reduced upper threaded portion of a stem or shank 6. The said reduced upper portion 7 projects from a head 8 and passes through the center of a cross bar 9 and clamps the same against the under- 45 side of the socket 5. The cross bar which projects equally beyond the opposite sides of the shank has its end portions curved to form supplementary grips and also to serve as stops to limit the downward movement of the ex- 50 tractor in forcing the same down through the cork for use in extracting the same. The lower end of the stem 6 is also formed with a reduced threaded portion 10 entering the threaded socket in the upper end of an intro- 55 ducing blade or knife 11. This blade or knife

is in the form of a thin wedge having a sharpened point and longitudinal side edges, so that it may be forced down through the cork and will cut a clean opening for its passage. Clamped between the lower end of the stem 60 and the upper surface of the introducing blade is a spring strip 12, the opposite ends of which are upturned to form curved hooks 13. This strip is normally straight and horizontal and rests squarely upon the plane upper edge of the blade, but beyond the stem 65 the opposite end of the strip are free to bend upwardly to the dotted line position shown in Fig. 2 to permit of the insertion of the device without resistance from said strip. When 70 applied, the oppositely projecting ends of the stem provide extracting hooks to engage the underside of the cork to effect the withdrawal thereof upon an outward relative movement between the extractor and bottle. 75

In the operation of extracting a cork, the extractor is disposed as shown in dotted lines in Fig. 2, the blade brought to bear against the outer end of the cork and then forced down through the cork, cutting a clean narrow slot to permit of its passage in the neck of the bottle below the cork. The ends of the spring strip 12 in this operation fold upwardly to the dotted line position in Fig. 1 through their pressure against the walls of 80 the slot to permit the shank 6 to pass with a minimum of resistance through the slot cut by the blade until it passes below the cork, whereupon the ends of the strip spring back 85 to normal position and the hooked extremities 13 bear against the underside of the cork, as shown. Upon then giving the extractor a quarter turn to dispose the blade at right angles to the length of the slot previously 90 formed thereby, the hooked ends of the strip 95 will be prevented from having downward movement by their bearing against the upper surface of the blade and will thus operate to form engaging devices extending under the cork, whereby when the extractor is drawn 100 outward pressure will be brought to bear upon the cork to effect its extraction from the neck of the bottle. Upon the removal of the cork the blade and strip may be detached to permit the cork to be drawn off the stem. 105 If an exceedingly refractory cork is encountered which cannot be withdrawn in the ordinary way, the handle 1 may be engaged with a hook or other object on the wall and the full strength of the operator exerted to pull 110

outward on the bottle, whereby the withdrawal of the cork may be effected.

It will be seen that by the provision of the cutting knife and extracting means associated therewith, the device may be forced through any cork and the latter then quickly and conveniently withdrawn.

Having thus fully described the invention, what is claimed as new is:—

- 10 1. A cork extractor comprising a stem, a cutting blade mounted upon the stem, hooked spring bearing members arranged for coöperation with the blade, and a handle applied to the upper end of the stem.
- 15 2. A cork extractor comprising a stem, a wedge-shaped cutting blade detachably mounted upon the lower end of the stem, a spring strip clamped between said blade and the stem and provided with outwardly yield-

ing extracting fingers having hook-shaped ends, and a handle applied to the upper end of the stem.

3. An extractor comprising a stem, a cross bar removably mounted upon the upper end of the stem, a handle applied to the stem and securing said cross bar in position, a tapering cutting blade detachably mounted upon the lower end of the stem, and a spring strip clamped between said blade and stem, said strip having its ends arranged to form yielding spring fingers provided with hook-shaped ends.

In testimony whereof I affix my signature in presence of two witnesses.

SARAH E. BRADDOCK.
